UNITED STATES PATENT OFFICE.

CHARLES G. WEAVER, OF CRYSTALSPRINGS, KANSAS.

WOOD-CARRIER.

1,118,519.

Specification of Letters Patent. Patented Nov. 24, 1914.

Application filed September 4, 1913. Serial No. 788,171.

To all whom it may concern:

Be it known that I, CHARLES G. WEAVER, a citizen of the United States, residing at Crystalsprings, in the county of Harper, 5 State of Kansas, have invented certain new and useful Improvements in Wood-Carriers; and I do hereby declare the following to be a full, clear, and exact description of the invention, such as will enable others 10 skilled in the art to which it appertains to make and use the same.

The present invention is directed to improvements in wood carriers, and has for its object to so construct a device of this 15 character that a number of short fire logs may be placed thereon and the carrier lifted to inclose the logs so that the same can be conveniently carried to their place of use.

A further object of the invention is to 20 provide a device of this character which is exceedingly simple in construction, durable and one which can be manufactured at a very small cost.

With these and other objects in view, this 25 invention resides in the novel features of construction, formation, combination and arrangement of parts to be hereinafter more fully described, claimed and illustrated in the accompanying drawing, in which:—

30 Figure 1 is a plan view of the device. Fig. 2 is an end view, showing the device in its operative position.

The carrier comprises a plurality of trans- 35 verse sheet metal bars 1, the same being ar- ranged in spaced parallel relation and have their terminals provided with perforations 2, while their intermediate portions are pro- vided with perforations 3.

Arranged in spaced parallel relation with 40 the outermost bars 1 are sheet metal bars 4, said bars also having their terminals pro- vided with perforations 5 and intermediate perforations 6.

The terminals of the bars 1 are alined 45 with the chain sections 7 so that the links thereof loosely engage the perforations 2 formed in the terminals of said bars, simi- lar sections 8 being provided for engaging the perforations 3 formed in said bars.

The bars 4 are of less length than the 50 bars 1 and are connected to the outermost bars 1 by chain sections 9, certain links of which engage the perforations 2 of the outermost bars, while the other links of said sections engage the perforations 5 formed 55 in the short bars 4. Chain sections 10 are also provided and have one of their ends engaging the perforations 6 of the bars 4 and their other ends the perforations 3 of the bars 1.

Connected to the perforations 5 of the short bars 4 are links 11, which are de- 60 signed to pivotally interlock with the eyes 12 formed on the ends of the handles 13.

From the foregoing description it will be 65 seen that upon placing logs upon the carrier and moving the handles 13 so that the same contact the device can be readily lifted to transport the wood.

What is claimed is:—

A wood carrier of the class described comprising a plurality of transverse bars, said bars having perforations formed in their terminals and intermediate thereof, short bars arranged in spaced parallel re- 75 lation with the outermost bars of the first named bars, said short bars having perforations formed in their terminals and inter- mediate thereof, chain sections connecting the terminal perforations of the bars, simi- 80 lar chain sections connecting the interme- diate perforations of said bars, curved links connected to the perforations in the terminals of the short bars, said links being constructed and arranged to bear against 85 the uppermost piece of wood being carried to force the other of said pieces outwardly against the chains, and handles having their ends connected to the links.

In testimony whereof, I affix my signa- 90 ture, in the presence of two witnesses.

CHARLES G. WEAVER.
